BURGLAR STOP.

Filed Nov. 26, 1945

UNITED STATES PATENT OFFICE

2,425,937

BURGLAR STOP

William Hilton, Seattle, Wash.

Application November 26, 1945, Serial No. 630,757

3 Claims. (Cl. 292—342)

1

This invention relates to window locks or what are sometimes referred to as "burglar stops," and it has reference more particularly to devices of that character designed to be applied to sliding sash windows to definitely limit the distance to which a window may be opened.

It is the principal object of this invention to provide a device of the character above stated comprising a plate designed to be fixed to one sash of the window and a stop element that may be adjusted to and secured at different locations on the plate, to be engaged by the other sash when it is moved toward an open position.

It is also an object of the invention to provide a device of the kind above stated, wherein the stop member limits the extent to which the window may be opened to a distance less than that required for a person to enter therethrough and may not be released by one at the outside of the window and may not be removed from the plate for opening the window to its full extent except while the window is completely closed.

Other objects and advantages of the invention reside in the details of construction of the parts of the device and in their mode of assembly and use as will hereinafter be fully described.

In accomplishing these and other objects of the invention, I have provided the improved details of construction, the preferred forms of which are illustrated in the accompanying drawings, wherein—

Fig. 1 is an elevation showing parts of the upper and lower sliding sashes of a typical window to which a burglar stop, embodied by this invention, is applied.

Fig. 2 is a front view of the burglar stop.

Fig. 3 is a central, longitudinal section of the same as affixed to a window sash.

Fig. 4 is a perspective view of the stop element of the device illustrating its securing stud.

Fig. 5 is an enlarged fragmental view of parts of the device, showing the upper end portion of the stop member partially broken away for better illustration of its holding stud and indicating, in dotted lines, the position to which the stop element is required to be turned relative to the base plate, in order that it may be shifted to a different location on the plate.

Fig. 6 is an enlarged, cross section on line 6—6 in Fig. 2.

Referring more in detail to the drawings—

In Fig. 1, 10 and 11, respectively, designate parts of the upper and lower sliding sashes of a typical form of a residence window; it being understood that these sashes are held slidably in a window frame of a suitable kind, a part of which

2

is designated at 12 in Fig. 1, and that the guideways in which the sashes slide are separated by a stop strip designated by reference character 13, as in Figs. 3 and 6.

5 The purpose of the present device, referred to as a burglar stop, is to limit the extent to which the lower sash may be raised or the upper sash lowered to a distance less than that required for a person to gain entry through the window, but 10 sufficient for ventilation or fresh air entry.

In its present preferred form of construction, the device comprises a flat, elongated base plate 15, preferably of metal, that is formed near its upper and lower ends, and at intermediate points 15 if so desired, with holes 16 for reception of securing screws. In Fig. 3, such screws are designated by reference character 17.

Formed about the marginal edges of the plate 15, on its inside, are ribs or flanges 18, designed 20 to space the body portion of the metal plate outwardly from the surface of the part to which it may be applied, as will best be understood by reference to Figs. 3 and 6.

Formed in the plate 15, lengthwise thereof, is 25 a slot 20 of uniform width. This slot is formed at regularly spaced intervals therealong with circular enlargements, as at 21, one of which is at the upper end of the slot. At its lower end, the slot 20 terminates in a circular enlargement 30 22 that is of substantially greater diameter than the enlargements 21 for a purpose presently explained.

The stop member that is associated with the base plate, is designated in its entirety by reference numeral 25. This comprises a metal block of wedge-like form, provided with a flat inside surface 25a designed to be engaged flatly against the outer surface of the base plate, lengthwise thereof and to be secured in a downwardly 40 pointed position thereon, as will be understood by its showing in Fig. 3.

Fixed in the stop member 25, near its upper or thicker end, and extending inwardly from the flat inner surface 25a thereof, is a securing stud 45 27, formed with a flat anchoring head 28. The stud 27 is flattened at top and bottom surfaces, as shown best in Fig. 5, wherein the cross sectional view shows it to have a thickness or diameter in the vertical direction that is slightly 50 less than the width of the slot 20, and it has a transverse diameter or thickness greater than the width of the slot 20 and just slightly less than the diameter of the circular enlargements 21. The head 28 of the stud is of a diameter 55 greater than that of the slot enlargements 21 but just slightly less than the diameter of the

lower end enlargement 22 and may be passed therethrough. Also extending from the inner face of the stop member, but near its lower end, is a short stud 30. This is of such diameter that it will be received within the slot 20 and the purpose of this stud is to prevent any lateral displacement of the lower end of the stop member from its holding position.

Assuming the device to be so constructed, it is applied and used as follows:

First, with both window sashes shifted to closed positions, the base plate 15 is applied lengthwise to one of the vertical stiles of the upper sash with its lower end terminating about at the level of the lower edge of the glass panel in the upper sash, and is secured by applying screws 17 through the holes 16. The stop member 25 is then applied to the base plate by turning it to a horizontally extending position, as indicated by its showing at 25x in Fig. 5, and then passing the head portion 28 of the anchoring stud through the opening or enlargement 22 at the lower end of the slot 20; it being understood that the head of the stud is of such diameter that it will not pass through any of the openings 21.

After the stud head has been passed through the plate opening 22, the stop, still in horizontal position, may be moved upwardly along the base plate to any of the selected stopping positions which are established by the enlargements 21 in the slot 20, then turned to a vertical position, and its flat inside surface 25a seated flatly against the base plate with the short stud 30 disposed within the plate slot 20.

It will be understood that when the stop, after being applied to the plate, is turned to the horizontal position, the stud 27 may then be secured in the slot 20 for movement therewith. When the stud has reached one of the enlargements 21 in the slot, then the stop may be rotated down to the holding position, and this turns the stud crosswise of the slot and causes it to be retained in the enlargement 21 as shown in Fig. 5. The anchoring stud cannot be unseated because head 28 cannot be passed through the slot 20 or any of the enlargements 21.

Should the lower sash be raised or the top sash lowered, the stop 25 will wedge against the top rail of the bottom sash, as illustrated in Fig. 3, thus to limit the extent of opening of the window in accordance with the position at which the stop has been set.

In order that the window may be opened completely, it is necessary first to completely close both sashes, then to swing the stop member 25 to a horizontal position and shift it along slot 20 to the lower end of the plate 15 and withdraw the anchoring stud 27 from the plate by passing the head 28 outwardly through the lower end enlargement 22 of the slot. With the stop removed, the window sashes are free for up and down adjustment to full extent permitted by the window frame.

With the present device, the extent of opening of a window may be limited to a few inches, or distances for desired ventilation without making possible the release of the stop and raising of the window by one outside the window.

A feature of importance is the provision of means requiring that the windows be entirely closed before the stop can be removed for complete opening of the window.

Having thus described my invention, what I claim as new therein and desire to secure by Letters Patent is:

1. A device of the character described comprising a plate adapted to be fixed adjacent the path of travel of a slidably mounted window and having a slot formed therein in the direction of window travel; said slot being formed, at intervals therewith, with enlargements, a stop member applied to the outer face of the said plate and adapted to be engaged by the window to limit its opening movement; said stop member having an anchor stud extended inwardly therefrom and through said slot within one of the slot enlargements and a head at the inner end of the stud for engaging the inner face of the plate to retain the stud against withdrawal from the slot, and said stud having a transverse thickness substantially fitting the slot enlargement to prevent movement of the stop along the plate when in a window holding position, and having a vertical thickness that is lesser than the width of the slot, whereby, upon turning the stop member to a position transversely of the slot, the stud is movable along the slot for the disposition of the stop at any selected holding position.
2. A device as recited in claim 1 wherein the stop member is in the form of an elongated wedge, and wherein the anchor stud extends inwardly from that end portion of greater thickness and a short stud extends inwardly from the inner face of the thinner end portion of the stop member into the slot to retain the stop against lateral turning when a window is engaged against the outer surface of the stop member.
3. A window stop device comprising a plate adapted to be fixed adjacent the path of travel of a slidably mounted window and having a slot formed therein in the direction of window travel and said slot having enlargements at spaced intervals therewith, a stop member of wedge-like form applied to the outer face of the said plate and adapted to be engaged along its outer surface by the window to limit its opening movement; said stop member having an anchor stud extended inwardly from its larger end through said slot within one of said enlargements thereof, a head on said stud engaging the inside of the plate for preventing withdrawal of the stud from the slot, a short stud extending from the stop into the slot to prevent lateral turning of the stop member while a window is engaged therewith; said anchor stud having a transverse thickness substantially fitting the slot enlargement to prevent movement of the stop along the slot when it is in holding position, and having a vertical thickness less than the width of the slot permitting adjustment of the stop along the plate slot when the stop is turned transversely thereto, for the disposition of the stop at any selected stopping position; and there being an enlargement at one end of the slot and through which the head of the anchor stud may be passed for removal of the stop from the plate.
